UNITED STATES PATENT OFFICE.

DANIEL HOWE, OF SALEM, NEW HAMPSHIRE.

DESIGN FOR A HORSESHOE.

SPECIFICATION forming part of Design No. 30,966, dated June 6, 1899.

Application filed May 12, 1899. Serial No. 716,591. Term of patent 14 years.

To all whom it may concern:

Be it known that I, DANIEL HOWE, a citizen of the United States, residing in Salem, in the county of Rockingham and State of New Hampshire, have invented and produced a new and original Design for a Horseshoe, of which the following description, in connection with the accompanying drawings, is a specification, like letters on the drawings representing like parts.

The design relates to a horseshoe; and it consists in a horseshoe distinguished by its peculiar shape, as will be hereinafter set forth and claimed.

Figure 1 is a plan view of a horseshoe embodying my design; and Fig. 2, a section on the line 2 2, Fig. 1.

As shown in the drawings, the leading fea-

ture of my design consists in the transversely-curved form of the tread portion or surface ²⁰ *a* of the horseshoe, which curved portion is substantially semicircular in shape in cross-section, and at the central front portion of the shoe the inner portion of the curve merges into a flat surface *b*.

²⁵

I claim—

The design for a horseshoe herein shown and described.

In testimony whereof I have signed my name to this specification in the presence of ³⁰ two subscribing witnesses.

DANIEL HOWE.

Witnesses:

JAS. H. CHURCHILL,
J. MURPHY.
